By Attorney

UNITED STATES PATENT OFFICE.

CARL H. VIEBROCK AND HENRY W. VIEBROCK, OF DOUGLAS, WASHINGTON.

VALVE-GRINDER.

1,397,390.

Specification of Letters Patent.

Patented Nov. 15, 1921.

Application filed February 2, 1921. Serial No. 441,830.

To all whom it may concern:

Be it known that we, CARL H. VIEBROCK and HENRY W. VIEBROCK, citizens of the United States, residing at Douglas, in the 5 county of Douglas and State of Washington, have invented certain new and useful Improvements in Valve-Grinders; and we do hereby declare the following to be a full, clear, and exact description of the invention, 10 such as will enable others skilled in the art to which it appertains to make and use the same.

This invention provides a tool designed specifically for use in grinding the valves of 15 internal combustion engines, but which is susceptible of general application in grinding of valves to their seats.

The invention aims to provide a valve grinding tool which is readily adjustable 20 within certain limits to a variety of valves and capable of being easily and effectively secured in the adjusted position.

The invention furthermore aims to provide a tool of the character aforesaid which 25 will maintain close engagement with the valve after being fitted thereto without slipping, even though the shank of the tool should be inclined from the perpendicular, provision against slipping being obviated 30 the inter-position of a universal joint between the head of the tool and its shank.

Other objects and advantages will be apparent and suggest themselves as the nature of the invention is understood.

35 While the drawings illustrate an embodiment of the invention it is to be understood that in adapting the same to meet different conditions and requirements, various changes in the form, proportion and minor details 40 of construction may be resorted to without departing from the nature of the invention.

Referring to the accompanying drawings forming a part of the specification,

45 Figure 1 is a view in elevation of a valve grinding tool embodying the invention.

Fig. 2 is a vertical central section of the head portion of the tool, the outer part of the stem being in full.

50 Fig. 3 is a horizontal section on the line 3—3 of Fig. 2.

Fig. 4 is a detail perspective view of the finger piece,

Fig. 5 is a detail perspective view of the nut,

Fig. 6 is a perspective view of the retainer, 55

Fig. 7 is a detail perspective view of the shank of the globose head,

Fig. 8 is a detail perspective view of the valve grips,

Fig. 9 is a top plan view of the adjuster 60 for the valve grips,

Fig. 10 is a sectional detail of the globose head and coöperating shank,

Fig. 11 is a detail perspective view of the globose head, and 65

Fig. 12 is a detail perspective view of a portion of the valve grip adjuster.

Corresponding and like parts are referred to in the following description and designated in the several views of the drawings 70 by like reference characters.

The tool comprises a stem and a head, the latter being connected with the stem by means of a universal joint. The stem is designated by the numeral 1 and its outer 75 end is constructed to be fitted to a brace or similar operating tool. The universal joint comprises a socket 2 and a globose member or head 3, the socket being of square form and the member 3 having its four sides 80 curved to conform to elements of a sphere. An equatorial section of the member 3 conforms to the square outline of the socket 2, hence rotation of the latter effects corresponding movement of the part 3, the curved 85 sides of the latter providing for the universal movement whereby to retain the head of the tool in close engagement with the valve, even though the stem 1 should incline in any direction from the perpendicular. 90 The socket 2 is pinned or otherwise secured to the stem 1 to rotate therewith. The globose head or member 3 is retained within the socket 2 by means of inturned ears 4 at the lower edges of the side walls of the socket. 95

The shank 5 of the globose head or member 3 is formed at its lower end with an outer flange 6 and is externally screw threaded, as indicated at 7, to receive a coöperating nut 8. The shank 5 is detachably connected 100 with the member 3 and may be pinned or otherwise secured thereto. The nut 8 is formed at its lower end with an outer flange 9 and at its upper end with lateral extensions 10. A butterfly or winged finger piece 105 11 coöperates with the nut 8 to effect rotation thereof on the shank 5 to clamp or release the valve grips as may be required.

A retainer 12 is loosely mounted upon the nut 8 between the flange 9 and lateral extensions 10 thereof. The central portion of the retainer 12 is raised, as indicated at 5 13, to receive the flange 9 of the nut 8. Diametrical openings 14 are formed in the flange 6 of the shank 5 to receive journals 15 of valve grips 16, the latter being of similar formation and consisting of sector-shaped plates disposed against the lower 10 face of the flange or head 6 of the shank 5. Studs or pins 17 project from the ends of the valve grips 16 and are adapted to enter the openings of the valve to be ground. The 15 studs or pins 17 are adapted to be adjusted to a greater or less distance apart to correspond with the varying positions of the openings in different types of valves.

To set the valve grips an adjuster is provided. This adjuster consists of a disk or 20 plate 18 having a rim 19 at its outer edge to inclose the valve grips, flange 6 and retainer 12. The upper edge of the rim 19 is inturned, as shown most clearly in Fig. 2, 25 to retain the parts in assembled position. Arcuate slots 21 are formed in the disk or plate 18 to receive the studs or pins 17. These slots have an opposed eccentric arrangement, as shown most clearly in Fig. 9, 30 whereby to effect a simultaneous like movement of the valve grips when the adjuster is operated, said adjuster operating similar to the scroll of a universal chuck.

When the parts are assembled they assume 35 the relative position indicated most clearly in Fig. 2. When the finger piece 11 is loosened the rim 19 of the adjuster may be gripped and rotated in one direction or the other to space the studs or pins 17 to agree with the 40 distance apart of the openings in the valve to be ground. After the tool has been set, the finger piece 11 is turned to effect clamping of the valve grips 16, this being accomplished by a binding of the part 16 between the plate 18 and the flange or head 6 of the shank 5. Relative inward movement of the 45 nut 8 effects a corresponding movement of the retainer 12 by engagement of the flange 9 therewith. The outer portion of the retainer 12 engaging the inturned edge 20 of the adjuster, causes the latter to move inward and thereby clamp the valve grips in the manner stated.

It will be understood from the foregoing 55 that a tool constructed in accordance with the present invention is susceptible of universal application because of the adjustment of the studs or pins 17 which enter the openings of the valve in a manner well understood. The tool may be readily and 60 conveniently set and when adjusted is made secure by tightening the nut 8 which may be easily effected through the instrumentality of the finger piece 11. When the tool 65 is in operation, it is prevented from slip-

ping by reason of the universal joint in the length of the stem, the head of the tool maintaining close engagement with the valve, even though the stem should incline slightly in any direction from the perpendicular. 70

It should be stated that the pins or studs 17 may be of any desired formation best adapted for the particular work in hand. They may be flared, straight or of any re- 75 quired outline.

What is claimed is:

1. A valve grinding tool comprising a stem, a head including a shank, a square socket in one of said parts, and a coöperating member on the remaining part and of square form in equatorial section to conform to the socket and having its four outer surfaces coinciding with elements of a sphere. 80

2. A valve grinding tool comprising a stem, a head including a shank, a square socket on one of said parts, and having in-turned ears at the outer edges of its inclosing walls, and a globose head connected 90 with the other member and fitting within said socket and retained in place by the said in-turned ears and forming therewith a universal joint connection between the stem and shank. 95

3. A valve grinding tool embodying valve grips, an adjuster for setting the valve grips, and means for clamping the valve grips in the adjusted position.

4. A valve grinding tool embodying complementary pivoted valve grips, having off-standing valve engaging studs, an adjuster for setting the valve grips by a pivotal movement, and means for clamping the valve grips in the adjusted position. 100

5. In a valve grinding tool, valve grips embodying plates provided upon one side with journals and having valve engaging studs upon the opposite side, an adjuster for setting the valve grips by a pivotal movement, and means for clamping the valve grips in the required adjusted position. 110

6. In a valve grinding tool, a shank provided with a head, valve grips relatively adjustable on the head, an adjuster for setting the valve grips, and a nut threaded on the shank and adapted to clamp the valve grips in the adjusted position. 115

7. In a valve grinding tool, a shank having a head, valve grips relatively adjustable on the head, an adjuster for setting the valve grips, a nut threaded on said shank, and means intermediate said nut and adjuster to effect a clamping of the valve grips in the required adjusted position. 120

8. In a valve grinding tool, a shank having a head, valve grips, an adjuster for setting the valve grips, a nut having screw thread connection with the shank, a retainer in coöperative relation with the nut and ad- 130

juster, a finger piece rotatable with the nut and having relative loose connection therewith.

9. In a tool of the character specified, a shank having an outer flange, movable valve grips having outwardly extending studs, a rotatable adjuster having opposed eccentrically arranged arcuate slots for the reception of said studs, and a nut on the shank 10 to secure the valve grips in adjusted position by means of a clamping action.

10. In a tool of the character specified, a shank having an outstanding flange, opposed valve grips pivotally connected to said 15 flange, a rotary adjuster having opposed arcuate shaped slots eccentrically arranged to effect adjustment of the valve grips, an outwardly flanged nut on the shank, and co-operating means between said nut and adjuster to effect a clamping of the valve grips.

11. In a tool of the character specified, a shank, pivoted valve grips having outwardly extending studs, a rotary adjuster having opposed arcuate slots eccentrically arranged 25 and receiving the said outwardly extending studs, a nut on the shank, and a retainer between said nut and adjuster to effect a clamping action of the latter.

12. In a tool of the character specified, a 30 shank, pivoted valve grips, a rotary adjuster for setting the valve grips, a nut on the shank and having lateral extensions, a retainer between the nut and adjuster, and a finger piece loose on the nut and engaging 35 the lateral extensions thereof to effect rota-

tion of the nut and a positive clamping of the valve grips.

13. In a tool of the character specified, a shank having an outer flange, valve grips having pivotal connection with said flange, 40 a rotary adjuster having opposed arcuate slots eccentrically arranged, a nut on said shank having an outer flange and lateral extensions, a retainer between said nut and adjuster and engaged by portions thereof, 45 and a finger piece loose on the nut and engaged by the lateral extensions thereof.

14. A tool of the character specified comprising a stem, a square socket at one end of the stem, an outwardly flanged shank 50 having a globose head at one end co-operating with the said socket to form a universal joint between the stem and shank, valve grips having pivotal connection with the outwardly extending flange of the shank, a 55 rotary adjuster having opposed arcuate slots eccentrically arranged, an outwardly flanged nut on the shank and having lateral extensions, a retainer between the nut and adjuster and engaging portions thereof, and a 60 finger piece loose on the nut and engaging the lateral extensions thereof.

In testimony whereof we affix our signatures in presence of two witnesses.
